APPARATUS FOR PRINTING AND EMBOS-
ING IN REGISTERCharles G. Bright, Appleton, Wis., assignor to
Paper Patents Company, Neenah, Wis., a cor-
poration of Wisconsin

Application September 29, 1934, Serial No. 746,095

5 Claims. (Cl. 101—23)

This invention relates to apparatus for printing and embossing in register, its chief intended use being for the printing and embossing of wall paper in multi-color designs.

5 Combined printing and embossing machines are broadly known, but, so far as I am aware, considerable difficulty has been experienced in securing accurate register of the printed and embossed areas on the paper, especially at high 10 speeds, and also in obtaining clearness and sharpness of the design on the product. It is the object of the present invention to improve the art in both of these respects, as well as to provide a machine that can be successfully operated at high speeds and with the use of thin 15 inks.

Apparatus embodying the novel principle of the invention is diagrammatically shown in the accompanying drawing, in which:—

20 Fig. 1 is an elevation of the several rolls and accessories for a machine designed to print and emboss in two colors.

Fig. 2 is a similar elevation of a machine designed to print and emboss in four colors.

25 Referring to Fig. 1, 10 designates a steel embossing roll, the periphery of which carries in relief portions, such as a, b, c, and d of a complete design, in this case repeated on each half of the roll periphery. Above and in rolling contact with 30 said embossing roll is an ink transfer roll 11 having an elastic surface 11a of rubber or gelatin composition adapted to receive design impressions. In rolling contact with the impression roll 11 are a pair of diametrically opposed cut 35 out metal printing rolls 12, each of which carries on its periphery portions, such as a, b and c, d, in relief of the complete design a, b, c, d on the embossing roll 10. Ink is fed to each of the printing rolls 12 from a pan 13 by an intaglio feed 40 roll 14, equipped with a doctor 14' and in rolling contact with a rubber surfaced transfer or form roll 15, which in turn, delivers the ink to the printing roll 12 and the design fraction or fractions on the periphery thereof. The ink, 45 which may be of different colors, as red and green, is pressed into the yielding elastic surface of the transfer roll 11, and these ink-covered impressions then travel into register with the raised design fractions on the embossing roll 10. Co- 50 operating with the steel embossing roll 10 is the usual paper impression roll 16, between which and the steel embossing roll 10 this paper web W to be printed and embossed passes.

55 Rolls 10 and 11 are of the same diameter, and rolls 12 are of one-half the diameter of 10 and

11, and all of these rolls are geared together so as to be in constant register. The design portions or fractions on each printing roll 12 are transferred to each half of the surface of the transfer roll 11. It will be understood, of course, 5 that the design fractions for the different colors are located so as to register with different parts of the pattern to avoid overlapping of the various colors.

Fig. 2 illustrates an extension of the same principle, designed to facilitate printing and embossing in register in a larger variety of colors. Here the transfer roll 11' is twice the diameter of the embossing roll 10' and four times the diameter of the printing rolls 12. This makes possible the 10 use of four printing rolls, and consequently the printing of the design in four different colors, the complete design being repeated on each quarter of the periphery of the transfer roll 11' and on each half of the periphery of the embossing roll 10'. Where a larger diameter transfer roll, such as 11', and a larger number of printing rolls 12 are employed, as illustrated in Fig. 2, 15 not only may a greater variety of embossing and color effects be obtained, but a greater amount 20 of detail in the complete design is also possible, as typically illustrated by the design portions or fractions e, f, g, h, i, k. And since the ink transfer roll is an even multiple in diameter of the printing rolls 12 and an integer or even multiple 25 in diameter of the embossing roll 10 or 10', the 30 complete design is impressed and printed on the paper web in successive areas with perfectly matched joints and with no overlapping.

The ink of the designs is not necessarily confined to the raised or embossing parts of the roll 10 or 10', since the surface of the roll 11 or 11' is sufficiently elastic or flexible to carry the colors into the lower areas of the embossing roll, 35 so that the printed design may appear on a background that is a combination or blend of the several colors employed. However, most of the color for the design is applied to the relief portions of the embossing roll.

As compared with known devices for printing 45 and embossing in register, the chief novel feature of this invention is the use of the offset ink transfer roll between the printing rolls and the embossing roll. By the use of this feature I have 50 found that I am able to use thin inks with consequent ease and speed of change to other colors, much simpler inking fountains may be employed than have heretofore been used, and it is practicable to use cut-out metal printing rolls instead of cut-out soft composition rolls, the for- 55

mer holding their sharpness of design much better and lasting longer than the soft rolls. Faster speeds and more perfect register of the cooperating rolls are also obtained by the present invention.

5. I claim as my invention:

1. Apparatus for printing and embossing in register, comprising, in combination, a cut out metal printing roll carrying a design in relief, 10 means for supplying ink thereto, an ink transfer roll having an elastic surface in rolling contact with said printing roll, an embossing roll carrying in relief the same design as said printing roll in rolling contact with said transfer roll, and a paper impression roll between which and said embossing roll the paper web to be printed and embossed is passed.

2. Apparatus for printing and embossing in register, comprising, in combination, a cut out metal printing roll carrying a design in relief, 20 means for supplying ink thereto, an ink transfer roll having an elastic surface in rolling contact with said printing roll, an embossing roll carrying in relief the same design as said printing roll in rolling contact with said transfer roll, said rolls being of the same, or even multiples of the 25 same, diameter, and a paper impression roll between which and said embossing roll the paper web to be printed and embossed is passed.

3. Apparatus for printing and embossing in register, comprising, in combination, a cut out metal printing roll carrying a design in relief, an ink pan, an ink feed roll dipping in said pan, a doctor cooperating with said feed roll, a form 30 roll having an elastic surface transferring the ink from said feed roll to said printing roll, an ink transfer roll having an elastic surface in

rolling contact with said printing roll, an embossing roll carrying in relief the same design as said printing roll in rolling contact with said transfer roll, said printing, transfer and embossing rolls being of the same, or multiples of the same, 5 diameter, and a paper impression roll between which and said embossing roll the paper web to be printed and embossed is passed.

4. Apparatus for printing and embossing in register, comprising in combination, a plurality 10 of cut out metal printing rolls each carrying a portion of a complete design in relief, means for supplying ink to said printing rolls, an ink transfer roll having an elastic surface and of a diameter that is an even multiple of the diameter of 15 said printing rolls in rolling contact with the latter, an embossing roll carrying in relief the complete design in rolling contact with said transfer roll, and a paper impression roll between 20 which and said embossing roll the paper web to be printed and embossed is passed.

5. Apparatus for printing and embossing in register, comprising in combination, a plurality 25 of cut out metal printing rolls each carrying a portion of a complete design in relief, means for supplying ink to said printing rolls, an ink transfer roll having an elastic surface and of a diameter that is an even multiple of the diameter of 30 said printing rolls in rolling contact with the latter, an embossing roll of the same diameter as, or an even fraction of the diameter of, said transfer roll carrying in relief the complete design in rolling contact with said transfer roll, and a paper impression roll between which and 35 said embossing roll the paper web to be printed and embossed is passed.

CHARLES G. BRIGHT.
